UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

AUTOMATIC STOKER.

Application filed July 1, 1922. Serial No. 572,190.

The present invention relates to furnaces or stokers of the type in which the fuel while in the course of combustion is fed progressively toward a discharge outlet 5 through which the refuse of the fuel is automatically discharged.

An object of the invention is to provide a novel and improved furnace of this character.

10 A more specific object of the invention is to provide novel and improved refuse crushing and expelling means for a furnace of this character.

Another object of the invention is to provide a novel and improved discharge outlet or ash pit for a furnace of this character.

With these and other objects in view the features of the invention consist in certain 20 constructions, arrangements and combinations of parts hereinafter described and claimed, the advantages of which will be obvious to those skilled in the art.

25 The several features of the invention will be clearly understood from the following description and accompanying drawings, in which,—

Figure 1 is a longitudinal sectional view of a portion of an automatic stoker of the 30 underfeed type embodying the features of the invention in their preferred form;

Figs. 2 and 3 are sectional plan views taken on the lines 2—2 and 3—3, respectively, of Fig. 1;

35 Fig. 4 is a detail sectional plan view on an enlarged scale taken substantially on the line 4—4 of Fig. 1;

Fig. 5 is an elevation of the portion of the stoker illustrated in Fig. 4;

40 Fig. 6 is a vertical section, partly in elevation, taken on the line 6—6 of Fig. 5;

Fig. 7 is a plan view of a portion of a modified form of refuse crushing and expelling means that may be used; and

45 Fig. 8 is a sectional view taken on the line 8—8 of Fig. 7.

The furnace illustrated in the drawings is provided with an underfeed grate section 2 and an overfeed grate section 3. The 50 underfeed grate section comprises a plurality of downwardly and rearwardly in-

clined retorts 4 that are arranged side by side and spaced apart, and the outer walls of the outer retorts are spaced from the side walls of the furnace, with rows of 55 tuyère blocks 5 spanning spaces between the margins of the adjacent walls of the retorts, and between the outer walls of the outer retorts and the side walls of the furnace. The several retorts and rows of tuyère blocks 60 constitute the upper wall of a wind box 6 to which compressed air is adapted to be supplied through a pipe 7, the supply of air being controlled by a damper 8 which is mounted in the pipe and operable from the 65 front of the furnace in the usual manner.

The overfeed grate section 3 is of box-like construction, and its rear wall is provided with tuyère openings and is curved downwardly and rearwardly as shown in 70 Fig. 1. Air is supplied to this grate section from the wind box 6 through a passage that is controlled by a damper 10. A depending apron 12 is mounted directly below the grate section 3 and together with 75 the grate section 3 forms the front wall of a discharge outlet or ash pit 14 extending the width of the furnace, the bridge wall 16 of the furnace forming the rear wall of the ash pit. The apron 12 is made 80 up of a plurality of sections (Fig. 3) that are provided with forwardly projecting hook members 17 at their upper ends which are pivotally hung on an angle iron 18 having its ends supported by brackets 20 adjacent the side walls of the furnace and projecting rearwardly from an I-beam 22. The lower edge of the apron when in closed position is seated in a groove 23 in the forward upper edge of a bar 25 extending between 85 the side walls of the furnace. The lower end of each section of the apron 12 is connected by a link 24 with the free end of an arm 26 secured on a shaft 28. The shaft 28 is mounted for pivotal movement in suitable bearings in brackets 30 secured to the I-beam 22. An actuating arm 32 is formed integral with one of the arms 26 and its free end is connected by a link 34 with the free end of the depending arm of a bell crank 36 90 pivotally mounted on a bracket at the front of the furnace. The other arm of the bell

crank 36 is in the form of a gear segment 38 which is engaged by a worm 40 carried by a vertical shaft 42 having a hand operated wheel 44 secured on its upper end.

5 With this construction it will be apparent that by turning the hand wheel 44 the apron 12 as a whole may be swung forwardly to permit access to the interior of the ash pit.

The upper portion of the bridge wall 16 is 10 provided with tuyère blocks 46 through which air may be supplied to the ash pit from an air passage 48 at the rear of the blocks which is connected with a suitable source of air supply. The bridge wall 16 is 15 further provided with a liquid spraying device 50 located adjacent the under side of the section of tuyère blocks and arranged to spray water or steam into the ash pit.

As illustrated the stoker is provided with 20 main feeding devices 52 for delivering the fuel from hoppers 54 at the front of the furnace to the several retorts, and is further provided with auxiliary feeding devices 56 for cooperating with the main feeding devices to feed the burning fuel longitudinally 25 of the retorts and toward the ash pit. As these fuel feeding devices are of a well known construction they are not specifically described herein.

30 The stoker illustrated in the drawings is provided with a plurality of rotatable clinker crushing and expelling devices which are arranged near the bottom of the ash pit with their axes extending fore and 35 aft of the furnace. These clinker crushing and expelling devices are arranged in pairs and are in the form of rolls 58 having the usual radially projecting crushing teeth 60. The left hand roll of each pair, viewing 40 Fig. 4, is mounted on a squared shaft 62 having its forward end extending through an aperture in the cross bar 25 and journaled in a bearing on an I-beam 64, and the other end of each shaft 62 extends through and is journaled in a bearing on an I-beam 66 that forms a support for the bridge wall 16. The right hand roll of each pair is secured on a shaft 68 having its forward end extending through an aperture in the cross bar 25 and 45 journaled in a bearing on the I-beam 64, and having its rear end portion extending through and journaled in a bearing on the I-beam 66 and its extreme end journaled in a bearing on an I-beam 67. The left hand roll 50 of each pair is rotated in a clockwise direction and the right hand roll of each pair is rotated in the opposite direction so that the rolls of each pair cooperate to crush and expel the clinkers and ashes downwardly between them. The rolls are thus actuated by 55 a crank shaft 70, journaled in bearings in the I-beams 66 and 67 and connected with the several shafts 62 and 68. The connections between the shafts 62 and 68 and the 60 crank shaft 70 comprise ratchet wheels 72

secured on the projecting rear end portions of the shafts, the ratchet wheels on the shafts 68 being spaced a distance back of the ratchet wheels on the shafts 62. The several ratchet wheels 72 are provided with actuating pawls 74 that are pivotally mounted between the arms of yokes 76 having their lower ends pivotally mounted on the shafts 62 and 68. The upper ends of the yokes 76 associated with the shafts 62 are all pivotally connected 75 with a reciprocating rod 78 which is connected by a link 80 with a crank-pin 82 of a crank formed on the crank shaft 70, and the upper ends of the yokes 76 associated with the shafts 68 are all pivotally connected with a reciprocating rod 84 which is connected by a link 86 with a crank-pin 87 of a crank formed on the crank shaft 70. The cranks on the crank shaft 70 associated with the rods 78 and 84, respectively, are arranged 80 diametrically opposite each other as shown in Fig. 5 so that upon rotation of the crank shaft 70 the rods are reciprocated in opposite directions with relation to each other and the teeth of the ratchet wheels 72 and the pawls 74 associated with the shafts 62 and 68, respectively, are so arranged that the clinker crushing and expelling rolls of each pair are rotated in the desired reverse directions upon the said reciprocations of the rods 78 85 and 84.

In the illustrated construction means is provided for regulating the speed of rotation of the clinker crushing rolls 58 independently of each other. As shown a yoke shaped lever 88 is pivotally mounted on each of the shafts 62 and 68 with the sides of each lever interposed between the ratchet wheel and the sides of the yoke 76. The upper ends of the levers 88 are each provided with a cross-piece 90 which serves as a shield adapted, when the lever 88 associated therewith is turned, to work over the teeth of its ratchet wheel and by engagement with the lower end of the associated pawl 74 to control the engagement of the pawl with the teeth of the ratchet wheel in accordance with the angular position of the lever, and thus control the extent of each intermittent movement imparted to each ratchet wheel by its 100 pawl. The angular positions of the controlling levers 88 are adapted to be independently adjusted by means of rods 92 pivotally connected with the lower ends of the levers 88, respectively, and extending to a convenient position outside of a side wall of the furnace.

As shown in Fig. 2 of the drawings there is a clinker crushing and expelling roll in alignment with each of the retorts and with each of the rows of tuyère blocks 4, and as shown in Fig. 3, the sections of the apron 12 correspond in number and arrangement to the rolls, so that the width of the stoker may be easily increased or made to such 110 115 120 125 130

dimensions as desired by merely increasing the number of these parts. This construction also enables the front and rear walls of the ash pit to diverge downwardly towards the clinker rolls, as shown in Fig. 1, thus insuring proper engagement of the ashes with the rolls, which is not the case in ash pits where the front and rear walls converge toward the clinker rolls as it has been found that in such prior construction the ashes are liable to become packed in the ash pit and not properly engage the rolls.

The beam 66 and the cross bar 25 on which the lower end of the apron 12 is seated, close the spaces between the ends of the rolls, so as to prevent the ashes from working out longitudinally of the rolls.

With this arrangement of the clinker crushing rolls it will be apparent that an unbroken clinker crushing and ash expelling surface is provided which is not obtainable in constructions in which the rolls are arranged at right angles to the present arrangement. In such prior constructions bearings for the shafts of the rolls are required at certain intervals and it has been found that clinkers are liable to form on these bearings that cannot be disposed of by the rolls. It will also be apparent that the provision for independent adjustment of the speed of operation of the clinker crushing rolls permits the rate of the discharge of the refuse for different areas of the ash pit to be varied as desired.

In the modified construction of refuse crushing and expelling means illustrated in Figs. 7 and 8 a series of clinker crushing rolls 94 is provided which rolls are spaced apart and arranged fore and aft of the furnace, and bars 96 extending between the side walls of the furnace are arranged between the rolls and have clinker crushing teeth 98 on opposite sides thereof which operate with the teeth on the rolls.

As will be evident to those skilled in the art my invention permits of various modifications without departing from the spirit thereof or the scope of the appended claims.

What I claim is:

1. A furnace having, in combination, a support for fuel in the course of combustion, a discharge outlet for the refuse of the fuel, means for feeding the fuel towards said outlet, a plurality of rotatable refuse crushing and expelling members mounted in said outlet with their axes extending in the general direction of the feed of the fuel, and means for rotating said members having provision for adjustment to vary the relative speed of rotation thereof.

2. A furnace having, in combination, a support for fuel in the course of combustion, a discharge outlet for the refuse of the fuel, means for feeding the fuel towards said outlet, a pair of rotatable refuse crushing

and expelling members mounted in said outlet with their axes extending in the general direction of the feed of the fuel, and means for rotating said members in opposite directions so as to cause the refuse to pass between them, each member being rotated continually in but one direction.

3. A furnace having, in combination, an underfeed grate section comprising a plurality of retorts and rows of tuyère blocks arranged in alternate relation, a discharge outlet for the refuse of the fuel, means for feeding the fuel while in the course of combustion towards said outlet, a plurality of rotatable refuse crushing and expelling members mounted in said outlet, alternate members being arranged with their axes in a plane with the axes of the retorts, respectively, and the other members being arranged with their axes in a plane with the axes of the rows of tuyère blocks, respectively, and means for rotating said members associated with said retorts and rows of tuyère blocks, respectively, in opposite directions.

4. A furnace having, in combination, an underfeed grate section comprising a plurality of retorts and rows of tuyère blocks arranged in alternate relation, a discharge outlet for the refuse of the fuel, means for feeding the fuel while in the course of combustion towards said outlet, a plurality of rotatable refuse crushing and expelling members mounted in said outlet, alternate members being arranged with their axes in the planes of the axes of the retorts and the other members arranged with their axes in the planes of the axes of the rows of tuyère blocks, respectively, and means for rotating said members associated with said retorts and rows of tuyère blocks, respectively, in opposite directions, having provision for adjustment to vary the speed of rotation of one or more of said members with relation to the others.

5. A furnace having, in combination, a support for fuel in the course of combustion, a discharge outlet for the refuse of the fuel means for feeding the fuel toward said outlet, a pair of rotatable refuse crushing and expelling members mounted in said outlet with their axes extending in the general direction of the feed of the fuel, and means for imparting an intermittent rotary movement to said members in opposite direction with relation to each other so as to cause the refuse to pass between them, each member being rotated continually in but one direction.

6. A furnace having, in combination, a support for fuel in the course of combustion, a discharge outlet for the refuse of the fuel, means for feeding the fuel toward said outlet, a pair of rotatable refuse crushing and expelling members mounted in said outlet with

their axes extending in the general direction of the feed of the fuel, and means for imparting an intermittent rotary movement to said members in opposite directions with relation to each other so as to cause the refuse to pass between them, said means having provision for adjustment to vary the extent of the intermittent movements of one of the members with relation to the other member.

7. A furnace having, in combination, an underfeed grate section, an overfeed grate section following the underfeed section, a discharge outlet for the refuse of the fuel adjacent the rear end of the overfeed section, means for feeding the fuel while in the course of combustion toward said discharge outlet, rotatable refuse crushing and expelling members located near the bottom of said discharge outlet having their axes extending in the general direction of the feed of the fuel, means for operating said members, and a movable apron constituting a portion of the front wall of the discharge outlet interposed between the overfeed section and said members.

8. A furnace having, in combination, an underfeed grate section, an overfeed grate section following the underfeed section and curved downwardly and rearwardly and having tuyère openings, means for directing air through said tuyère openings, a removable apron extending downwardly from the lower end of said overfeed section, a wall spaced back of said overfeed section and apron to cooperate therewith to form a discharge outlet for the refuse of the fuel, said wall having openings for the admission of fluid into said outlet, and a plurality of rotatable refuse crushing and expelling devices having their forward ends arranged below and adjacent the lower end of said apron and their rear ends arranged adjacent the rear wall of the discharge outlet.

9. A furnace having, in combination, a support for fuel in the course of combustion, a discharge outlet for the refuse of the fuel, means for feeding the fuel towards said outlet, a plurality of rotatable refuse crushing and expelling rolls mounted in said outlet with their axes extending in the general direction of the feed of the fuel, and means for intermittently rotating said members comprising ratchet wheels secured to said members, respectively, pawls for actuating said ratchet wheels actuating levers on which the pawls are mounted, and means for actuating said levers comprising a pair of reciprocating rods, connections between one of the rods and the levers associated with alternate rolls, and connections between the other rod and the levers associated with the other rolls, means for imparting reciprocating movements to the rods in opposite directions with relation to each

other, and independently operable devices associated with said pawls, respectively, for controlling the extent of the intermittent movements imparted to each ratchet wheel.

10. A furnace having, in combination, an underfeed grate section, an overfeed grate section following the underfeed section, a discharge outlet for the refuse of the fuel having its front and rear walls diverging downwardly, means for feeding the fuel while in the course of combustion toward said outlet, and a plurality of rotatable refuse crushing and expelling members mounted near the lower end of said discharge outlet with their axes extending in the general direction of the feed of the fuel.

11. A furnace having, in combination, a support for fuel in the course of combustion, a discharge outlet for the refuse of the fuel, the side walls of the furnace forming the side walls of said outlet, means for feeding the fuel toward said outlet, and an ash discharging means extending the width of said outlet having provision for adjustment to vary the rate of the discharge of the ashes at points spaced different distances from a side wall of the furnace.

12. A furnace having, in combination, a support for fuel in the course of combustion, a discharge outlet for the refuse of the fuel; means for feeding the fuel toward said outlet, a plurality of refuse crushing and expelling rolls mounted in said outlet, arranged in the general direction of the feed of the fuel, spaced apart and having clinker crushing teeth, and bars arranged between said rolls having clinker crushing teeth for cooperating with the teeth on the rolls.

13. A furnace having, in combination, a downwardly and rearwardly inclined underfeed grate section, an overfeed grate section at the rear of the underfeed section, an ash pit at the rear of the overfeed section having its front and rear walls diverging downwardly, and refuse crushing and expelling means comprising a clinker crushing roll arranged at the bottom of said ash pit, said rear wall being inclined downwardly and rearwardly from said front wall from substantially the upper level of the material in the ash pit.

14. A furnace having, in combination, a downwardly inclined underfeed grate section, an overfeed grate section following the underfeed section, an ash pit at the rear of the overfeed section having its rear wall inclined downwardly and rearwardly from substantially the upper level of the material in the ash pit and its front wall inclined downwardly and forwardly so as to provide downwardly diverging walls, and refuse crushing and expelling means comprising a clinker crushing roll arranged at the bottom of the ash pit.

15. A furnace having, in combination, a

downwardly inclined underfeed grate section, an overfeed grate section at the rear of the underfeed section, and an ash pit at the rear of the overfeed section having the upper portion of its rear wall inclined downwardly and rearwardly and comprising a plurality of air admitting blocks

covering an area extending from near the upper level of the fuel to the lower portion of the ash pit, the front and rear 10 walls of the ash pit diverging downwardly, and refuse expelling means at the lower end of the ash pit.

EDWIN LUNDGREN.
